ATTORNEY.

UNITED STATES PATENT OFFICE

157,649

TABLE

James E. White, Los Angeles, Calif.

Application December 6, 1948, Serial No. 150,012

Term of patent 14 years

(Cl. D33—14)

To all whom it may concern:

Be it known that I, James E. White, a citizen of the United States, residing at Los Angeles, State of California, have invented a new, original, and ornamental Design for Table, of which the following is a specification, reference being had to the accompanying drawing, forming a part thereof.

The drawing is a view showing in perspective my new design for a table.

I claim:

The ornamental design for a table, substantially as shown.

JAMES E. WHITE.
